THERAPEUTIC TABLET

Irving B. Wershaw, New York, N. Y., assignor to
 Dome Chemicals Incorporated, New York,
 N. Y.

No Drawing. Application April 2, 1942,
 Serial No. 437,409

4 Claims. (Cl. 167—58)

My present invention relates to a new preparation in tablet form adapted to be used for making a solution for wet dressings, compresses, wet packs, and immersion baths.

It is the main object of the present invention to provide for a new, therapeutically active, solid, and stable preparation in tablet form which contains all ingredients needed for producing a solution for wet dressings.

Another object of my present invention consists of producing tablets of the above type which are stable and thus storable for a practically unlimited time as long as they are kept dry and which nevertheless dissolve easily and quickly in water.

Still another object of my present invention consists of selecting the ingredients of these tablets in such a manner that the same can be easily compressed and hold firmly together after compressing.

With the above objects in view, my new preparation consists of a compressed mixture of dry acetate powder, aluminum sulphate and one or more binding agents bonding the particles of said acetate powder and said aluminum sulphate together; the acetate used has to be adapted to form aluminum subacetate when mixed with aluminum sulphate and water. It is furthermore indispensable from the point of view of the present invention that the aluminum sulphate used for these tablets be in a state substantially preventing reaction between this aluminum sulphate and the dry acetate powder contained in the tablets.

I have found that for the new preparation many different acetates may be used, such as the acetates of magnesium, cadmium, barium, strontium, and other similar metals; I prefer, however, to use calcium acetate as with this acetate I have obtained the best results.

The above mentioned effect, namely that the aluminum sulphate should be in a state substantially preventing reaction of this sulphate with the acetate present in the tablets, can be obtained in the most different ways.

Thus, for instance, I may coat the aluminum sulphate particles and thereby avoid reaction between them and the acetate present in the tablets. However, such a coating may retard the time of reaction during dissolution of the tablet in water, and is therefore not the best and simplest way of attaining the above described effect.

Another proposal to obtain the desired effect is based on the observation that the affinity of the aluminum sulphate and the acetate is the

greatest when they are used in powdered form, irrespectively of the fact whether this powder is added to the tablets in granulated or in ungranulated state. It should be stressed that the term "granulated" as used above and in the following description and claims indicates that the "granulated" substance has originally been in powder form, has then been mixed with a binding material and water, and thereafter dried. 5 Thus, each particle of such a "granulated" substance consists of a number of particles of this substance itself and binding material holding these particles together. If two substances, each of which is in granulated form, are mixed and compressed, this compressed mixture finally consists of nothing more than the powdered particles of these substances held together by a binder. The contacting surfaces of these powdered particles are therefore relatively large in comparison with the amount of the substances contained in the compressed mixture; this results in a very great affinity of these substances.

It has been found that by using crystalline aluminum sulphate the single crystals of which have 25 a substantially larger size than that of the single acetate powder particles, I obtained very good results, i. e., the affinity of crystalline aluminum sulphate of the above type and granulated acetate powder proved to be substantially less than 30 the affinity between these same substances when they are both in powdered or granulated state. This makes possible combination of all needed ingredients in one single tablet without any danger of reaction as long as this tablet is kept dry. 35 It should be stressed that the term "crystalline" as used above and in the following description and claims defines not a "granulated" substance consisting of single particles composed each of powder particles of this substance and a binder, but 40 a mass composed of uncrushed not powdered particles, namely, "crystals" of this substance. The size of such crystals is in most cases—also if not separately indicated—larger than the size of particles of a powder made of this substance.

45 The acetate used for the new preparation is in granulated state, i. e., an acetate powder is used which is thoroughly mixed with a binding material and water; thereby the mixture of acetate and binder is granulated; thereafter, the 50 granulated acetate is thoroughly dried. The preferably crystalline aluminum sulphate granules are thoroughly mixed with another binder in dry state, preferably a water soluble starch or the like; the admixture of such a binder is advantageous as it bonds the particles in dry state

very well to each other and easily dissolves when the tablet containing it is placed in water. Thus, such a binder accelerates decomposition of the tablet in water and does not retard the reaction between the aluminum sulphate and acetate contained in it.

Thus, the finished tablet consists of two mixtures, namely of a granulated acetate consisting of acetate powder thoroughly mixed with a binding agent, as gelatin, acacia, or the like, and of an intimate mixture of aluminum sulphate and a binder which is easily soluble in water, for instance a water soluble starch or the like. These two mixtures, in turn, are thoroughly mixed before being compressed into tablets.

In order to avoid sticking of the mixed ingredients to the punches of the tablet making machine during compressing, boric acid powder is added as so-called lubricant. It is evident that also other substances adapted to serve as lubricants may be used instead of this boric acid.

A preparation which proved to be very satisfactory therapeutically contains 30% to 40% of powdered calcium acetate, 0.6% to 1.2% of powdered acacia, 40% to 60% of aluminum sulphate in crystalline granular state, 8% to 15% of a water soluble starch, and a small percentage, preferably not more than 3%, of powdered boric acid; all these ingredients are in completely dry state and after thorough mixing are compressed into tablets which are solid and stable, i. e., may be stored without any danger of decomposition for a practically unlimited time.

Tablets of the type claimed by me can, for instance, be produced in the following way:

First, about 50.6 parts of dry granular aluminum sulphate in crystalline state are intimately mixed with about 12.4 parts of dry soluble starch and about 1.5 parts of powdered boric acid. The granules of the aluminum sulphate are of such a size that they may be put through a No. 16 sieve; the starch and boric acid are in powder form and are put through a No. 20 sieve before being added to the crystalline aluminum sulphate; the sulphate, starch, and boric acid are then thoroughly mixed.

Then, separately from the above mixture, about 34.5 parts of calcium acetate are finely granulated with about one part of acacia and thereafter dried. Both the calcium acetate and the acacia are in powder form and are put through a number 20 sieve before granulation. This granulation is carried out in a well-known way, i. e., by slowly adding water to a mixture of these acetate and acacia powders while stirring and kneading the mixture. When the mixture is thoroughly granulated, it is put through a No. 6 sieve and then thoroughly dried for several days at a temperature ranging from 75° to 100° centigrade. During drying, it is advisable to stir the granulated mass several times in order to allow thorough and even drying.

Thereafter these two mixtures, namely, the sulphate, starch and boric acid mixture on the one hand and the granulated calcium acetate-acacia mixture on the other hand, are thoroughly mixed. The thus prepared final mixture represents the finished mass for the new preparation. This finished mass is then compressed into tablets in well-known way, for instance by means of a so-called Stokes tablet machine. The tablet produced in this manner is solid and stable when stored in a dry cool place and its ingredients will not react with each other without being dissolved in water.

Each of these tablets contains about 50.6% of granular aluminum sulphate in crystalline state intimately mixed with about 12.4% of a soluble starch and about 1.5% of powdered boric acid, and about 34.5% of powdered calcium acetate finely granulated with about 1% of acacia.

I have found that when I made tablets weighing each about 2.27 grams from the above mixture and dissolved two of these tablets in a pint of water, an aluminum subacetate solution was formed in an accurately measured concentration very adapted to be used for wet dressings. The reason for this is that the dissolving of tablets containing aluminum sulphate and calcium acetate in water results in a basic aluminum acetate solution with a precipitate of calcium sulphate and acetic acid according to the formula:

This basic aluminum acetate solution is then used as a wet dressing in all cases where such a dressing is advisable.

It will be understood that each of the elements described above, or two or more of them together, may also find a useful application in other preparations differing from those described above.

While I have illustrated and described the invention as embodied in preparations for making wet dressings, I do not intend to be limited to the details shown, since various modifications and structural changes may be made without departing in any way from the spirit of my invention.

Without further analysis, the foregoing will so fully reveal the gist of my invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What I claim as new and desire to secure by Letters Patent is:

1. A therapeutically active solid and stable preparation in tablet form, consisting of a compressed mixture containing a dry water-soluble metallic acetate powder adapted to form aluminum subacetate when mixed with aluminum sulphate and water, dry crystalline aluminum sulphate in not-powdered form the single crystals of which have a substantially larger size than that of the single particles of said metallic acetate powder, and at least one binding agent bonding the particles of said metallic acetate powder and the crystals of said aluminum sulphate together.

2. A therapeutically active solid and stable preparation in tablet form, comprising a compressed mixture containing dry powdered calcium acetate, dry crystalline not-powdered aluminum sulphate, the single crystals of which have a substantially larger size than that of the single particles of said acetate powder, and at least one binding agent bonding the particles of said powdered calcium acetate and said dry crystalline aluminum sulphate together.

3. A therapeutically active solid and stable preparation in tablet form, comprising a compressed mixture containing a dry water-soluble granulated metallic acetate powder adapted to react with aluminum sulphate and to form aluminum subacetate when mixed with aluminum sulphate and water, dry crystalline aluminum sulphate in not-powdered state the single crystals of

which have a substantially larger size than that of the single metallic acetate particles of said granulated metallic acetate powder and at least one binding agent bonding said dry crystalline aluminum sulphate and said granulated metallic acetate powder together.

4. A therapeutically active solid and stable preparation in tablet form, comprising a compressed mixture containing dry granulated cal-

5 cium acetate powder, crystalline aluminum sulphate in not-powdered state the single crystals of which have a substantially larger size than that of the single calcium acetate particles of said granulated calcium acetate powder, and a binding agent bonding said crystalline aluminum sulphate and said granulated calcium acetate powder together.

IRVING B. WERSHAW.
